COMBINED CROSS AND PEACE SYMBOL

Marvin Le Croy Hicks, 22 Melville Ave.,
Greenville, S.C. 29605

Filed Apr. 11, 1973, Ser. No. 349,964

Term of patent 14 years

Int. Cl. D11—02

U.S. Cl. D29—23 A

FIG. 1

FIG. 2

FIG. 3

FIG. 4

FIG. 1 is a perspective view of a combined cross and peace symbol showing my new design;

FIG. 2 is a side elevational view thereof;

FIG. 3 is an elevational view of my new design taken at a right angle to FIG. 2; and

FIG. 4 is a top plan view thereof.

I claim:

The ornamental design for a combined cross and peace symbol, substantially as shown.
